UNITED STATES PATENT OFFICE.

FRANK MACHAVA, OF SOUTH GREENSBURG, PENNSYLVANIA.

LOCKING MECHANISM FOR SLIDING CAR DOORS.

Application filed October 7, 1925. Serial No. 60,988.

My invention relates to a locking mechanism for sliding car doors, and the primary object of the invention is to provide a device of the character described which will prevent the entrance of unauthorized persons to railroad cars, equipped therewith.

Further objects of the invention are to provide a device of the type stated, in a manner as hereinafter referred to, which is simple in its construction and arrangement, strong, durable and efficient in its use, and comparatively inexpensive to manufacture.

With the foregoing and other objects in view which will appear as the description proceeds, the invention resides in the combination and arrangement of parts and in the details of construction hereinafter described and claimed, it being understood that changes in the precise embodiment of the invention hereinafter disclosed can be made within the scope of what is claimed without departing from the spirit of the invention.

In the drawing forming a part of this specification and wherein like numerals of reference designate corresponding parts throughout the several views:—

Figure 1 is a fragmentary side elevational view of the interior of a railroad car provided with a door securing mechanism constructed in accordance with my invention.

Figure 2 is a side elevational view of the locking mechanism with the casing cover removed therefrom.

Figure 3 is a sectional view on line III—III, Figure 2.

Figure 4 is a sectional view on line IV—IV, Figure 2.

Figure 5 is a longitudinal cross sectional view of the key bolt with associated parts.

Figure 6 is a side elevation of the key.

Figure 7 is a fragmentary top plan view of the rear end of the car door and associated parts.

Referring in detail to the drawing 1 designates the side wall of the railroad box provided with the usual sliding door 2 supported by hangers 3. The rear end of the door 2 is provided with hooked holders 4, which engage in apertured ears 5, fixed in the marginal edge of the outer side of the door opening for securing the rear end of the door 2 when the latter is in the closed position.

The door locking mechanism is mounted on the inside of the car side wall and com-

prises a rectangular casing 6 which is fixed to the side of the car by means of bolts 7. The cover 8 is secured to the casing 6 by means of the bolts 9, and the forward portion 10 thereof is hinged as at 11, for the purpose to be described. A flat spring 12, carried by the cover 8 and engaging the hinged portion 10, normally acts to force the latter to the open position.

The latching bar 13 is shiftably mounted on a fixed guide block 14 in the casing 6 and the rear upper end thereof is pivotally connected, as at 15, to the lower end of the connecting block 16. The latter extends through an elongated slot in the top wall of the casing 6 and has its upper end fixed to the gear bar 17, slidably mounted on the outer face of the top wall of the casing 6. A caster 18 is carried on the lower end of the latching bar 13 and travels on the inner face of the lower wall of the casing 6. The latching bar 13 is mounted to permit of longitudinal movement thereof in the casing 6, and also the lateral movement of the forward end which is formed to provide a latching hook 18, adapted to engage the associated apertured locking plate 19, carried by the door 2, for securing the latter in the locked position. A flat spring 20 is carried by the casing 6 and engages the outer side of the latching bar 13 for normally forcing the latching hook 18 inwardly and into engagement with the associated locking plate 19.

An actuating yoke 21 is pivotally connected, as at 22, in the casing 6 and engages the inner side of the latching bar 13 for forcing the latter outwardly against the action of the spring 20 when releasing the latching hook 18 from the locking plate 19, in the manner to be described.

The actuating yoke 21 is provided with a forwardly extending projection 23 which is engaged by the head 24 fixed to the top of the vertically disposed pin 25. The pin 25 is eccentrically mounted in the gear 26, which latter is rotatably mounted on the bottom wall of the casing 6.

The key bolt 27 is rotatably mounted in the casing 6 the outer end 28 thereof projecting through the car side wall 1, while the inner end 29 is journaled in the casing cover 8. The key bolt 27 is provided with a rectangularly shaped aperture 30 open at the outer end 28 and adapted for the recep-

tion of the rectangularly shaped body portion 31 of the key 32. The bolt 27 is provided at its top with a slot 33. A plug 34 is mounted in the slot 33 and is supported 5 therein by a spring 35 which is fixed to the periphery of the bolt 27 as indicated at 36. The lower end of the plug 34 normally depends into the aperture 30 and is provided with a tapered outer wall 37. The depending portion of the plug 34 normally closes the reduced aperture 38 formed in the key bolt 27 and prevents the operation of the locking mechanism by an implement other than the key intended therefor, in a manner 10 to be described.

The key bolt 27 is provided at its top and adjacent to its rear end with a notch 39 extending in alignment with the reduced aperture 38 and open at its upper end. The 20 notch 39 is intended for the reception of the lower end of the catch 40 which is pivoted, as at 41, in the casing 6. The upper end of the catch 40 is engaged by a spring 42, fixed in the casing 6. The action of the 25 spring 42 normally operates the catch 40 to engage in the notch 39 and lock the key bolt 27 against rotation.

The key 32 is provided with a slide 43 embedded in the body portion 31 and which 30 carries a projecting pin 44. The latter may be drawn into the body portion 31 if the slide 43 is pulled back when the key is not in use. The catch 40 is released from its engagement in the notch 39 by inserting the 35 key 32 into the key bolt aperture 30. The body portion 31 on entering the latter will engage the tapered plug wall 37 thereby forcing the plug 34 out of the aperture 30. After the key 32 has been inserted in the 40 aperture 30, the slide 43 is shoved inwardly causing the pin 44 to enter the reduced aperture 38 and disengage the catch 40 from the notch 39, thereby permitting of the rotation of the bolt 27 by the key 32 to operate 45 the locking mechanism in the manner hereinafter described.

A gear bar 45 is shiftably mounted in respective guides 46 and 47 fixed in the casing 6. The top of the bar 45 is provided with gear teeth 48, which mesh with the actuating gear 49 formed on the periphery of the key bolt 27, adjacent to the rear end of the latter. The outer side of the bar 45 is also provided with gear teeth 50 which mesh with the 55 gear 26. The rear end of the bar 45 carries a spiral spring 51, which abuts against the guide 47 and normally acts to force the bar 45 forwardly in the casing 6.

After inserting the key 32 in the bolt 27 60 and thereby releasing the catch 40 from the notch 39, as above described, the key 32 is turned in the counter clockwise direction, causing the gear 49 in mesh with the gear teeth 48, to shift the bar 45 rearwardly in 65 the guides 46 and 47. As the gear teeth

50 are in mesh with the gear 26, the latter will be rotated by the movement of the bar 45, thereby causing the head 24, connected to the gear 26 by the pin 25, to engage the yoke projection 23. Such engagement will 70 actuate the yoke 21 to force the rear end of the latching bar 13 outwardly and release the latching hook 18 from its engagement with the locking plate 19 and allow the opening of the car door 2.

The latching bar 13 being longitudinally shiftable in the casing 6, the former is automatically shifted forwardly in the latter so that the latching hook 18 will be completely retracted, in the casing 6 when the device 80 is in the unlocking position. This will prevent the latching hook 18 from being an obstruction when loading or unloading freight cargo through the door opening.

The automatic retraction of the latching bar 13 is effected by the movement of the operating rod 51' slidably supported in the brackets 52, 53 and 54, which latter are fixed in upper end of the car wall 1. A collar 55 is fixed on the rod 51, and a spiral spring 56 is mounted on the rod 51 intermediate of the collar 55 and the bracket 53. The action of the spring 56 normally tends to force the rod 51 rearwardly. A bumper 57 is fixed in the rear end of the rod 51' and extends outwardly through an elongated slot formed along the upper end of the side wall 1. The bumper 57 is arranged in the path of travel of the door hanger 3 and is shifted thereby when the door 2 is drawn to the closed position.

A gear 58 is rotatably supported on the car side wall 1 and meshes with the gear bar 17. The gear 58 is also in mesh with the gear bar 59 mounted on the lower end of the connecting rod 60. The upper end of the latter is fixed to the rod 51' and shifts therewith.

A guide plate 61 is secured to the lower end of the casing 6 and is formed with an elongated slot 62. A clamping rod 63, carrying a rotatable roller 64, is rigidly connected to the lower end of the connecting rod 60 and extends through the slot 62, of the guide plate 61.

A forwardly tapered block 65 is mounted on the cover hinged portion 10, of the cover 8, and is engaged by the roller 64 for clamping the hinged cover portion 10 in the closed position when the device is in the unlocked position.

When shifting the car door 2 to the closed position the hanger 3 will strike the bumper 57 thereby forcing the operating rod 51' forwardly. The forward movement of the rod 51' and of parts fixed thereto, will operate the gear 58 to shift the gear bar 17 in the reverse or rearward direction. As the latter is connected to the latching bar 13, by the block 16, the latching bar 13 will also be

shifted rearwardly and project the latching hook 18 from the casing 6. Upon the forward movement of the rod 51', the roller 64 will release the hinged cover portion 10, 5 whereby the latter and the latching bar 13 will be permitted to shift inwardly to position the latching hook 18 in engagement with the locking plate 19.

When the car door 2 is unlocked and 10 shifted to the open position, the action of the spring 56 will effect the retraction of the latching hook 18 into the casing 6.

What I claim is:

1. In a locking mechanism for a railroad car sliding door, the combination of a casing being adapted to be secured to the wall of the car and provided with a cover, a latching bar pivotally connected at its rear end in said casing, a yoke pivotally connected in said casing and engaging the inner side of said latching bar, said cover having a hinged forward portion shiftable inwardly to the open position to permit of the inward lateral movement of the forward end 25 of said latching bar to the locking position, means carried by said car door and engaging said hinged cover portion for releasing the latter when said car door is shifted to the closed position, a spring mounted in said casing and engaging the outer side of said latching bar for shifting the latter laterally inward to the locking position when said cover portion is released, and a key bolt mounted in said casing and operable to actuate said yoke for shifting said locking bar 30 to the unlocking position, substantially as described and for the purpose set forth.
2. In a locking mechanism for a railroad car sliding door, the combination of a casing being adapted to be secured to the wall 40 of the car and provided with a cover, a latching bar pivotally connected at its rear end and longitudinally shiftable in said casing, a yoke pivotally connected in said casing and engaging the inner side of said latching bar, 45 said cover having a hinged forward portion shiftable inwardly to the open position to permit of the inward lateral movement of the forward end of said latching bar to the locking position, means carried by said car door and engaging said hinged cover portion for releasing the latter when said car door is shifted to the closed position, a spring mounted in said casing and engaging the outer side of said latching bar for shifting the latter laterally inward to the locking position when said cover portion is released, and a key bolt mounted in said casing and operable to actuate said yoke for shifting said locking bar 50 to the unlocking position, substantially as described and for the purpose set forth.

In testimony whereof I affix my signature.

FRANK MACHAVA.
